EXCAVATING MACHINERY

Original application filed September 18, 1929, Serial No. 393,562. Divided and this application filed January 12, 1931. Serial No. 508,070.

This invention relates to a method of loading heavy excavating machines on railway cars for shipment and for unloading such excavating machinery from railway cars at the point of use.

The present application is a division of my pending application for excavating machinery, filed September 18, 1929, Serial No. 393,562.

10 In excavating machinery of this kind designed to handle a three cubic yard shovel dipper or a three and a half cubic yard drag-line bucket or larger or smaller buckets depending upon the length of the boom required, the machine, as a whole as well as its component parts, is of such unusually large size as to present a serious and difficult problem in connection with the shipping of the machine from the place of its manufacture to 20 the place of its use or in the shipping of the machine from one place of use to another. In fact, heretofore, it has been necessary to ship such a machine disassembled and then set it up or assemble it at the place of use. It is easy to appreciate that these practically 25 complete assembly and disassembly operations which are incident to each shipping result in considerable expense as well as the expenditure of a great deal of labor and the loss of time.

The type of excavating machinery to which the present method is applicable usually include a main frame, traction devices and a drive for the traction devices and has these 30 instrumentalities so organized that the traction devices at both sides of the machine may be easily removed as units to permit the main frame and all of the parts carried thereby except the boom to be shipped on a flat car. Booms in this type of machine are already 40 easily removed and with the present invention the boom and the traction devices are shipped on a separate flat car. All that is required for removing or replacing the traction devices is the removal of a few bolts and nuts, the traction devices and main frame and elements of the drive of the traction devices being engageable and disengageable 45 from each other by a relatively lateral shifting movement. Laborious and difficult as-

sembly and disassembly operations are avoided.

The method involved in the present invention is, in its broader aspects, directed to the application and removal of separate traction devices to the main frame of an excavating machine and consists in supporting the main frame independently of the traction devices, supporting the traction devices at either side of the machine, shifting the traction devices laterally to engage them with or disengage them from the main frame and applying or removing the fastening devices utilized for securing the traction devices to the main frame. In carrying out the loading of the machine onto a car for shipment the method involves running the excavating machine up into position wherein its traction devices are supported partly on the car and partly on temporary supports provided along the car, supporting the main frame independently of the traction devices, disconnecting the traction devices from the main frame and shifting them over onto the temporary supports and then lowering the main frame onto the car.

In carrying out the unloading operation the method involves providing temporary supports along the side of the car, elevating the main frame, placing the traction devices on the temporary supports, then securing them to the elevated main frame and then running the machine off of the car on its traction devices.

Referring now to the drawings:

Figure 1 is a diagrammatic view in elevation showing how a complete excavating machine is first brought into position with the main frame of the machine and the parts carried thereby properly overlying a flat car;

Figure 2 is a view similar to Figure 1 but showing the traction devices removed and the main frame lowered into position on the flat car;

Figure 3 is a view very similar to Figure 2 but showing the traction devices entirely removed;

Figure 4 shows the traction devices mounted on a flat car;

Figure 5 is a view partly in top plan and

partly in horizontal section illustrating the main frame and the traction devices and the drive therefor and showing how these parts are assembled and disassembled; and

5. Figure 6 is a view in elevation of that side of the main frame from which the traction devices have been removed.

Referring to the drawings, the numeral 1 designates generally the main frame of a machine which is supported, as will be hereinafter more fully described, on traction devices 2 of the type having endless flexible treads or self-laying tracks. A revolving platform 3 is supported on the main frame 1 for rotation in the usual manner and this revolving platform carries the boom, the power plant and the other instrumentalities of the machine which are well known and widely used and are therefore not shown.

20. Referring now especially to Figures 5 and 6, it will be seen that the main frame 1 has on each of its sides two outwardly projecting lugs 5 which may be cast integral or otherwise suitably connected to the body of the main frame. The outer face 5' of each lug 5 is machined to a flat plane surface and the under surface of the outer end portion of each lug is similarly machined to present a downwardly facing shoulder 6. In the assembly, the lugs 5 engage and are supported on brackets designated generally at 7 and integral with or otherwise fixedly connected to the frames 8 of the traction devices 2. Each bracket 7 has a machined face 7' adapted to fit flush up against the machined face 5' of its lug 5 and the lower portion of each bracket 7 is formed with a machined seat or shoulder 9 upon which the correspondingly formed shoulder 6 of the associated lug 5 rests. When the lugs 5 at either side of the main frame and the brackets 7 of the associated traction devices are brought into proper assembled relation, bolt holes 10, 11 and 12 on each lug are alined with correspondingly positioned bolt holes 13, 14 and 15 formed in the associated brackets 7 and adjacent portion of the traction frame 8. The bolt holes 11 and 14 are recessed or countersunk as indicated at 11' and 14', respectively, to define a pocket for the reception of a key or washer 16 so that the bolts and nuts 18 extending through the bolt holes 10, 11, 12, 13, 14 and 15 need only take the strain of holding the parts assembled and are relieved of all shearing stresses. In other words, the coacting shoulders of the lugs and brackets take the vertical load and the keys 16 take the stresses set up by the tendency of the traction frames to shift lengthwise relative to the main frame.

Each traction frame 8 has one end bifurcated as at 20 to receive the adjustable bearings 21 for a shaft 22 carrying idle sprocket wheels 23 which mesh with the pins 24 of the links 25 of the endless flexible treads. The

ends of the shaft 22 project beyond the sprocket wheels 23 and are received in the openings of I-bolts 26. Nuts 27 and 28 are threaded on the I-bolt 26 and engage the opposite sides of apertured bearing wings or abutments 29 cast integral with the traction frame 8 or otherwise suitably fixed thereto and through the openings of which the shanks of the I-bolts extend. The opposite end of each traction frame 8 has a bearing 35 for the reception of a drive shaft 30 on which driving sprockets 31 are keyed, the driving sprockets 31 coacting with the pins 24 of the links 25 to positively drive the flexible treads. On each shaft 30 adjacent the inner driving sprocket 31, a driven gear wheel 32 is fixed and is enclosed in a gear casing 33. Each shaft 30 extends inwardly beyond its driven gear wheel 32 and gear casing 33 and has its inner portion 34 adapted to be journaled in a bearing 35 provided in the main frame. A removable lock collar 36 is provided for the inner end of each shaft 34 and when the shaft 34 is received in its bearing 35 in the main frame, the collar 36 is releasably secured in position by a set screw or lock screw 37 and coacts with the adjacent surface of the main frame to hold the shaft 34 against outward displacement. Each gear casing 33 has an opening 38 in its inner face to permit of the passage into and out of the casing of a drive pinion 39. Each driving pinion 39 is positioned just alongside of the adjacent outer side member of the main frame 1 and is designed to intermesh with the driven gear 32 when the machine is assembled. These drive pinions 39 are preferably fixed on the outer ends of sleeves 42 and the sleeves 42 are rotatably mounted on a transverse drive shaft 43 driven from the power plant of the machine by means of the usual gearing 41. Clutches 40 serve to clutch the sleeve shafts 42 to the drive shaft 43 when desired. The ends of the drive shaft 43 project beyond the drive pinions 39 and are adapted to be received in flanged bearing openings 45 in the gear casing 33.

A machine so constructed and organized may be conveniently disassembled and assembled for shipment in accordance with the following novel method. The machine is completely assembled at the place of its manufacture and may be run under its own power up a suitable ramp and onto a flat car F and supporting structure or framing S built up alongside of the flat car, as clearly shown in Figure 1. The main frame is then jacked up, jacks J being positioned below portions 50 of the main frame. The traction devices are then removed, by taking out the bolts 18, removing the set collars 36 and shifting the traction devices laterally away from the main frame. Such lateral shifting of the traction devices disengages the gears 32 from their driving pinions 39 and pulls the shafts 130

34 out of their bearings as well as disengages the coacting lugs 5 and brackets 7. The jacks J are then manipulated to lower the main frame down onto the flat car, as illustrated in Figures 2 and 3. The traction devices may be shipped separately on a flat car as shown in Figure 4 and usually the boom is also mounted on the flat car with the traction devices. Assembly of the traction devices with the main frame may be carried out on the flat car by jacking up the main frame, placing the traction devices on suitable supporting structure S built up alongside of the flat car, shifting the traction devices laterally to bring the shafts 34 into the bearings 35, the gears 32 and 39 into mesh, and the brackets 7 into engagement with the lugs 5, and then assembling and securing the bolts and nuts 18 and the set collars 36. The traction devices are complete self-contained units carrying the adjustment for the idle sprockets and the driven gearing for the driving sprockets and are assembled and disassembled as units.

25 The invention claimed is:

1. The herein-described method of loading on to a car for shipment an excavating machine of the type having a main frame and traction devices removably secured thereto which consists in providing temporary supports along the sides of the car, running the excavating machine up into position wherein its traction devices are supported partly on the car and partly on said temporary supports, supporting the main frame independently of the traction devices, disconnecting the traction devices from the main frame and shifting them over on to the temporary supports, and then lowering the main frame on to the car.

2. The herein-described method of unloading an excavating machine of the type having a main frame and separate traction devices adapted to be removably secured to the main frame and in which the main frame is supported directly upon the car during shipment and which consists of providing temporary supports along the side of the car, elevating the main frame, placing the traction devices on the temporary supports, then securing them to the elevated main frame and then running the machine off of the car on its traction devices.

55 In witness whereof, I hereto affix my signature.

ROLF LJUNGKULL.
